[57] CLAIM

The ornamental design for an overhead luggage stowage bin for aircraft, substantially as shown and described.

DESCRIPTION

FIG. 1 is a front perspective view of my new design of an overhead luggage stowage bin for aircraft;

FIG. 2 is a left-side elevational view thereof;

FIG. 3 is a right-hand elevational view thereof; and

FIGS. 4, 5, 6 and 7 are front, bottom, plan, and rear views respectively of the overhead luggage stowage bin for aircraft, shown in FIG. 1.
